UNITED STATES PATENT OFFICE.

THOMAS J. POLLARD, OF CRANSTON, AND LEWIS S. DARLING, OF PROVIDENCE,
RHODE ISLAND.

CHAIN-CLASP.

1,360,678.

Specification of Letters Patent. Patented Nov. 30, 1920.

Application filed July 12, 1920. Serial No. 395,754.

To all whom it may concern:

Be it known that we, THOMAS J. POLLARD and LEWIS S. DARLING, citizens of the United States, residing at Cranston and Providence, respectively, in the county of Providence and State of Rhode Island, have invented certain new and useful Improvements in Chain-Clasps, of which the following is a specification.

10 Our invention relates to improvements in chain clasps, such as are used for ornamental chains as ordinarily worn about the neck and for chains used for other similar purposes, and the purpose of our invention is to provide a clasp that is cheaply made, quickly engaged, and that will hold the ends of the chain firmly together until removed by the wearer. We accomplish these purposes by the device shown in the accompanying drawings, in which—

Figure 1 is a plan view of the receiving member of the clasp.

Fig. 2 a section of the receiving member, together with the entering member after engagement, and

Fig. 3 a cross-section on the line $x-x$ of Fig. 2.

In Fig. 1, A represents a spiral or hollow helix formed of ordinary round jeweler's wire of gold or any other suitable material.

As shown in Fig. 2 in section, the spaces between the wires in the interior of the helix form in effect a female screw and from the nature of a helix this screw is of flexible or expansive character. The helix is attached to one end of the chain in any suitable manner.

The entering member B is attached to the other end of the chain and consists of a 40 tapering flattened piece, preferably of metal, having serrated edges as shown in Fig. 2, the projecting teeth being of such shape and position as to engage what answers to the interior threads formed by the helix in the manner aforesaid. The member B is inserted into A in the same manner as a screw is inserted into a nut, and is revolved in the ordinary manner until the engagement is complete. By virtue of the fact that 45 A is in the form of a spiral, and is there-

fore expansible and yielding, and that B is tapering, as shown in the drawing, it follows that as the member B is screwed into the member A, the latter expands at its outer end and by the elasticity of the spirally wound wire maintains a firm connection with the entering member B so that detachment of the two by accident is practically impossible.

It will be seen from the foregoing description that the expansible or yielding character of the helix A and the tapering shape of the member B are of the utmost importance in our invention.

It is evident that the spaces between the 65 teeth on the edges of the member B need not be exactly as shown in the drawing as one or more teeth may be omitted, all that is required being a sufficient number of teeth properly spaced so as to make proper engagement between the spirals of the member A.

In Fig. 3 is given a cross-section through the combined receiving member A and the entering member B. In this figure C represents a cross-section of the wire composing the helix. The dotted line a represents the expanded circle due to the entrance of the tapering member B.

The flattened member B, as shown in the 80 drawings, can be stamped upon an ordinary jeweler's press from flat stock in enormous numbers at a trifling expense, without the use of special machinery.

Having now described our invention, what 85 we claim and desire to secure by Letters Patent is:—

1. In a chain clasp, an entering member, tapering longitudinally, and adapted to enter and by its tapering form, expand a flexible receiving member, substantially as set forth.

2. In a chain clasp, an entering member consisting of a flattened body relatively thin, tapering longitudinally and provided 95 with serrated edges, the serrations being so spaced as to engage a part of or all the spaces between the coils of a helical receiving member, substantially as described.

3. A chain clasp comprising a flexible re- 100

ceiving member of hollow helical form; and a flattened longitudinally tapering entering member, adapted to be struck up out of flat stock and provided with serrated edges, the serrations being so spaced as to engage a part of or all the spaces between the helical coils of the receiving member, substantially as specified.

In testimony whereof we affix our signatures in presence of two witnesses.

THOMAS J. POLLARD.
LEWIS S. DARLING.
